FIG. 3

Des. 190,464

PAGE 3

FIGURE 4

FIG. 5

FIG. 6

Figure 1 is a bottom perspective view of an elevated storage tank of this invention;

Figure 2 is a bottom perspective view of a modified form of the elevated storage tank shown in Figure 1;

Figure 3 is a fragmentary cross-sectional view taken on line 3—3 of Figure 2;

Figures 4 and 5 are bottom perspective views, respectively, of modified forms of the elevated storage tank shown in Figure 1; and

Figure 6 is a fragmentary cross-sectional view taken on line 6—6 of Figure 5.

This is a continuation of our design applications, Serial Numbers D52,856, D52,857, D52,858, and D52,859, all of which were filed on October 2, 1958.

We claim:

The ornamental design for an elevated storage tank as shown and described.
